Primary Examiner—T. Chase Nelson*Assistant Examiner*—Mark Cavanna(74) *Attorney, Agent, or Firm*—Muncy, Geissler, Olds & Lowe, PLLC(57) **CLAIM**

The ornamental design for a shower controller with display, as shown and described.

DESCRIPTION

FIG. 1 is a perspective view of a shower controller with display showing our new design;

FIG. 2 is a left side view thereof;

FIG. 3 is a right side view thereof;

FIG. 4 is a front view thereof; and,

FIG. 5 is a top view thereof with the bottom view being a mirror image thereof.

The rear surface of the shower controller with display is unornamented.

The dashed lines illustrate environment that does not form a part of the present invention, and no claim is made to the material illustrated with dashed lines.
